J. Wright
Smoking Meat.
No 15,452. Patented July 29 1856.

UNITED STATES PATENT OFFICE.

JOHN WRIGHT, OF WILMINGTON, DELAWARE.

IMPROVEMENT IN APPARATUS FOR SMOKING MEATS.

Specification forming part of Letters Patent No. 15,452, dated July 29, 1856.

To all whom it may concern:

Be it known that I, JOHN WRIGHT, of the city of Wilmington, in the county of New Castle and State of Delaware, have invented a new and Improved Mode of Smoking Meats, Fish, &c.; and I do hereby declare that the following is a full and exact description thereof, reference being had to the accompanying drawings, and to the letters of reference marked thereon.

The nature of my invention consists in providing outside of the building used for smoking (A) furnaces with a grate and fire-plate so formed as to cause all the smoke generated to pass into the house, and in setting up or building inclined flues with smoke stoppers and spreaders, so that the smoke generated will pass throughout the house, smoking the meat, &c., evenly in any part of the building, and in less time than is generally taken for such purposes, besides preventing dust or ashes from falling upon the meat, &c., besides preventing fire damaging the building or heating the meat.

To enable others skilled in the art to make and use my invention, I will proceed to describe its construction and operation.

In building the smoke-house A, I lay the foundation of stone or brick two feet deep, twelve inches thick, and nine feet square. I then run up the walls fifteen feet high on the lowest or furnace side of the building, and on the highest or entrance side sixteen feet, giving the roof a pitch of about one foot in eight.

The walls may be of the thickness of eight or nine inches; but four and a half inches are thick enough for the smallest-sized buildings.

In running up my walls I set in a piece of three-by-four scantling, about nine feet from the floor of the building, on the inside, running across the front and back walls. I then set in a like piece about twelve inches from the first one, and others, until I get to the top of the lowest wall.

For smoking herring I use three or more pieces of the same-sized scantling cut so as to slip between the walls, their ends resting upon the pieces *a a a*, built in the walls. I use like movable scantlings filled with hooks to hang meats, &c., upon. As to the material for roofing, a shingle, board, or pebble roof will answer.

I ventilate the house by a door in the roof *b*, which in this sized house is twelve by fifteen inches in size, which I open or close by means of a rod. By opening this door the smoke passes off and sufficient light is admitted for all purposes.

In constructing the furnaces A A A, I pave with brick, about eight feet from the smoke-house, the whole length of the building. I make the furnaces about three feet high, with the end and division walls four and a half inches thick, (marked 1 1 1 in the drawing B;) the grates B B B twenty inches wide, twenty-eight inches deep; the doors of cast-iron, eleven by twelve inches. The whole length and breadth of the grate underneath the thick cast-iron or sheet-iron rests upon the walls and forms an air or smoke chamber, C, in size four by twenty-two inches, by which arrangement the draft is increased and all the smoke generated passes into the inclined flues D D D, and none is lost, as is often the case otherwise, when the contents of the furnace drop into the ash-chamber beneath the grate.

The inclined flues in the first place connect with smoke-chamber C, passing through the wall of the house, and are eight inches square about six inches from the top of the pavement. I build the wall E across the building four and a half inches thick, leaving holes eight inches in diameter for sheet-iron collars eight inches in length. The flues D D D, which are composed of brick, earthenware, or iron, or other incombustible material, I lay after having packed in earth between the walls until I obtain the desired inclination. I then, provided I build of brick, lay a header-course of brick upon the earth from the bottom of the entrance of the flue to the opening in the inner wall, E. The length of flues should be three-fourths the width of the house—in a house of this size, (about eight feet inside,) say six feet. I lay the first course of brick without mortar, the course to be laid lengthwise against the row of headers also without mortar; then three other courses laid in mortar on each side of the first course of headers. The last course I draw over a little, so as to give the last course of headers a bearing of half an inch on each side, which forms the flue. The brick flue is easier cleaned than any other.

I leave an opening fourteen inches from the

wall, and build up with brick level with the pavement, and build a sheet-iron collar therein. I also make another upright flue four and a half feet from the first, (the first marked F, the second G, in the drawing.) I then fill in and cover the flues with earth packed, and pave the top with brick, giving the pavement an ascent of about six inches from the inner wall to the wall of the house. This pavement I lay even with the upright or vertical flues or pipes F G.

The openings in the flues I stop with caps of sheet-iron when but little smoke is needed, and use the smoke-spreader, which will fit any opening. This smoke-spreader, which is shown at or upon the vertical flue G in the plan A, consists of a circular piece of tin or iron supported by wires attached to a rim made to fit the collars or openings, and is about twelve or fifteen inches in diameter, and set about eighteen inches above the rim to which it is attached. This little spreader will break the column of smoke arising and spread it all over the house.

My building, nine feet square, fifteen feet

high, with these flues, will smoke five thousand herrings in three days, at a cost of seventy-five cents. These furnaces and flues can be erected or attached to any smoke-house already built, and the house not likely to take fire from the furnaces or sparks from the pipes, although the building be frame.

What I claim as my invention, and desire to secure by Letters Patent, is—

The application to furnaces of smoke-houses of a back plate of iron or other incombustible material, forming an air-chamber which will increase the draft of the furnaces and prevent any smoke from being wasted or lost, and also the application of inclined flues made of brick, iron, earthenware, or any other incombustible material, together with the smoke-spreaders, as herein fully described, for the purpose of smoking meats, &c., the furnaces being upon the outside of the building.

JOHN WRIGHT.
